FLOOR WAXING DEVICE

Henry C. Henninger, Ridgewood, N. J.

Application February 6, 1934, Serial No. 709,936

10 Claims. (Cl. 91—25)

Special objects of this invention are to provide a simple, practical and inexpensive device for applying liquid wax, polish or other liquid coatings to floors and the like.

Other objects of the invention and the novel features of construction, combinations and relations of parts by which the same are attained are set forth and will be apparent from the following specification.

10 The drawing accompanying and forming part of the specification illustrates one practical embodiment of the invention, but as such illustration is primarily for purposes of disclosure, it will be appreciated that the structure and modification 15 may be changed in various ways all within the true scope of the invention as set forth in the claims.

Fig. 1 is a side elevation of the device showing the pull wire operated to open the valve controlling discharge from the bottom of the can.

Fig. 2 is an enlarged broken sectional view illustrating particularly the clamp mechanism for holding the can to the stick or handle and the combination can-puncturing and valving lever.

Figs. 3, 4 and 5 are cross sectional details as on lines 3—3, 4—4 and 5—5 of Fig. 1.

In its simplest form, the invention comprises a suitable handle such as a stick 7, carrying a 30 mop, brush or the like 8, adapted for distributing the wax, oil, polish or other liquid and means on said handle for securing a can of the wax or other liquid and for puncturing the can and then valving the contents of the same.

35 In the illustration, there is shown at 9, a can such as ordinarily used for packaging liquid wax and like floor finishing materials. Such cans are usually provided with screw caps such as indicated at 10, but this is not essential or necessary to the present invention. The can in fact may be entirely sealed, reaching the user in that state. Actually this is preferred, since the container is less expensive and the user is assured of the original contents put up by the manufacturer of the floor wax or other material.

When mounted ready for use, the bottom of the can is punctured, in the illustration by a point 11, carried by a lever 12, pivoted at 13, on a sleeve-like bracket 14.

50 This bracket is shown as a split sleeve, Fig. 5, which is gripped upon the handle stick in the desired position by thumb screw 15.

The lever mounting bracket or sleeve also carries a positioning and supporting lug 16, which 55 as shown in Figs. 2 and 5, grips behind the rim

or flange 17, about the bottom of the can and thereby positions the can backed solidly against the sleeve.

At the top, the can is shown held by another split sleeve 18, Figs. 2 and 4, adjustably fastened on the stick by thumb screw 19, and having a down-turned lug 20, engaging over the rim 21, at the top of the can to hold it backed against this top sleeve.

In practise it will be seen that it is only 10 necessary to loosen the upper thumb screw 19, whereupon the sleeve 18, can be lifted enough to permit the can being engaged over the supporting lug 16, of the lower clamp bracket, whereupon the upper bracket may be slid down into 15 tight engagement over the upper can flange and the thumb screw 19, be tightened. The can will then be held rigidly on the stick and in position for the bottom of the same to be pierced by the puncturing element 11.

It is usually sufficient simply to force the lever 12, by hand toward the bottom of the can, but if necessary, the end of the lever may be tapped with a hammer or the like, to drive the puncturing point through the bottom of the can.

The taper of the puncturing point enables it to serve also as a valve for preventing unwanted escape of liquid, but to make sure of perfect seal, a washer or gasket 22, of rubber, cork or the like, may be carried by or surround the prong in position to seal against the bottom of the can. To hold the valving element normally closed, a spring 23, is shown acting on the outer end portion 24, or extension of lever 12, and opening movements of the valve are provided for by a pull connection 30 35 25, extending up the handle and having a convenient finger hook 26, on the upper end thereof.

This pull connection is shown as a wire or light rod having its upper end formed as a loop 27, sliding about the handle, said rod sliding down 40 through a guide lug 28, projecting from the upper end of the lower clamp sleeve and having its lower end bent or shouldered at 29, after passage through the lever extension 24. The guide lug 28, serves as an abutment for the valve closing 45 spring 23, being engaged by the washer or cup 30, over the upper end of the spring.

To prevent the pull link from simply dropping down away from the valve lever when the latter is in the closed position indicated in Fig. 2, a 50 shoulder or abutment such as the kink or bend 31, may be formed on the wire to engage the guide lug 28.

To permit the parts being packed in small space, the pull link may be made in two or more 55

different lengths pivotally hooked together at their meeting ends as indicated at 32, Fig. 1 and at these joints, one or both of the rod lengths may carry loops 33, sliding over the stick.

- 5 The device consists of but few simple parts and these may be packed in small space for shipping purposes and be readily assembled by the user or concern marketing the invention. The cans of material may be sealed by the manufacturer of the same, guaranteeing the user against fraud. These cans are readily mounted on the stick or handle and when so mounted, the material is immediately available by simply forcing the puncturing point into the bottom of the can.
- 10 15 When this is done, the material may be discharged under perfect control through the operation of the pull link connected with the puncturing and valving lever. While the device is primarily a floor waxing implement, it will be realized that it may be used for other purposes and that this term therefore is not a limiting expression. Similarly other words and phrases have been employed herein in a descriptive rather than in a limiting sense, except possibly as limitations may be imputed by state of the prior art.

What is claimed is:

1. A floor waxing or like device, comprising in combination, a handle and liquid distributing means carried thereby, a can of the liquid to be applied, means for securing said can in fixed supported relation on the handle, a movable puncturing and valving element mounted on the handle in position to cooperate with said can, means for holding said puncturing and valving element in a normally closed relation to the can and means for shifting said element to control escape of the liquid through the opening punctured in the can.
- 20 25 30 35 40 45 50 55 60 65 70 75 80 85 90 95 100
2. A device for distributing floor wax and the like, comprising a handle, a distributing member carried thereby, a can of the material to be distributed, means for removably fixing said can in supported relation on the handle, a puncturing and valving element mounted on the handle in position to puncture the bottom of the supported can and to thereafter valve release of the contents through the punctured opening and means for controlling said puncturing and valving element.
3. A device of the character disclosed, comprising a handle stick, means for clamping a can in definitely supported relation on said handle stick and means on the stick for puncturing the bottom of a can so supported on a stick, said means being movable to thereafter serve for valving the punctured can.
4. A device of the character disclosed, comprising a handle stick, means for clamping a can in definitely supported relation on said handle stick, means on the stick for puncturing the bottom of a can so supported on the stick, said means be-

ing movable to thereafter serve for valving the punctured can and control mechanism for shifting said combination puncturing and valving element to control release of the can contents at will.

5 In a device of the character disclosed, a support, clamp mechanism on said support for removably securing a liquid containing can thereon, a lever mounted on the support and carrying a point for puncturing a can supported thereon and means on the support for effecting movement of said puncturing lever to effect valving of the contents of the punctured can.

6 In combination, a handle, a liquid distributing head carried thereby, a liquid containing can, adjustable clamps on the stick for removably supporting said liquid containing can in definitely supported relation thereon, a lever carried by the stick and provided with a point positioned for puncturing the can, a spring for holding said lever in position with the point engaged in a punctured opening in the can made by said point and means for effecting release of the lever from such position.

7 In a combination, a supporting member, relatively adjustable can clamping members on said member, a lever mounted on one of said clamp members, a can puncturing point carried by said lever, a spring for shifting said lever in the can puncturing direction and control means for shifting the lever in the opposite direction.

8 In combination, a supporting stick, split sleeves secured in relatively adjustable relation on said stick, a liquid containing can held between said relatively adjustable sleeve members and a can puncturing and valving lever mounted on one of said sleeve members.

9 In combination, a support, adjustable clamp means for removably securing a liquid containing can on said support, a movable member mounted on said support, a puncturing point carried by said member for forming a discharge opening in a can mounted on the support and valve seal material associated with said can puncturing point.

10 In combination, a support, adjustable clamp means for removably securing a liquid containing can on said support, a movable member mounted on said support, a puncturing point carried by said member for forming a discharge opening in a can mounted on the support, valve seal material associated with said can puncturing point, including a gasket of compressible material about said point and adapted to engage the can wall about the punctured opening, spring means for holding the lever in the can sealing position and control connections for shifting the lever in the opposite direction.

HENRY C. HENNINGER.
